UNITED STATES PATENT OFFICE.

KENNETH AIRD AND SQUIRE ARCHIBALD DAVID WEBSTER, OF FALKIRK, SCOTLAND,
ASSIGNORS TO R. AND A. MAIN LIMITED, OF EDMONTON, LONDON, ENGLAND, A
BRITISH COMPANY.

GAS STOVE.

Application filed November 29, 1921. Serial No. 518,600.

To all whom it may concern:

Be it known that KENNETH AIRD and SQUIRE ARCHIBALD DAVID WEBSTER, subjects of the King of Great Britain, residing at 5 Falkirk, Scotland, have invented certain new and useful Improvements in Gas Stoves, of which the following is a specification.

This invention relates to that class of gas stove described and illustrated in our British Patent No. 152191 and consists principally in so constructing the fuel plate as to support the firebrick back, the burner and injector nozzle and in providing said plate with devices to position the radiants in relation to the burner nozzles, the burner being supported by the fuel plate at three points to give flexibility. The invention is applicable to other types of gas stoves and also comprises other elements of construction as hereinafter set forth.

The present invention will be fully understood from the following description in connection with the annexed drawings which illustrate an example of our invention applied to an inset gas stove and in which—

Figure 1 is a top plan view of the fuel plate.

Figure 2 a front elevation of the fuel plate.

Figure 3 a side elevation of the fuel plate.

Figure 4 is a section on the line *a—a* of Figure 1.

Figure 5 is a section on the line *b—b* of Figure 1.

Figure 6 is a section on the line *c—c* of Figure 1.

Figure 7 is a transverse vertical section of a gas stove embodying the invention.

Figure 8 is a top plan view of the gas stove shown in Fig. 7, the dogs being shown 40 in section.

Figure 9 is a perspective view of the stove complete.

According to this invention the fuel plate 6 is provided with a hooked projecting lug 45 12, which lug extends over the upper edge and engages the back wall 11 of a supporting structure.

From the lower side of the fuel plate adjacent the rear edge of same depend two 50 saddle pieces 13 which bear against the front

face of the back wall 11 of the supporting structure and which receive and support the lugs 15 projecting rearwardly from the burner 14. A plurality of holes 16 are formed in the fuel plate 6 just forwardly of 55 the saddle pieces 13, and projections 17 are formed on the upper side of the fuel plate in advance of a line passing through the centers of the holes 16, and other projections 18 somewhat larger than the projections 17 60 are formed on the upper surface of the fuel plate to the rear of said line. A plurality of holes or apertures 19 are formed in the fuel plate 6 between the projections 18. These holes 19 serve to admit air from beneath the fuel plate 6 to the space between 65 the radiants 2 and the fire back 1. Such air not only assists in preventing overheating of the fire back but as it passes between the radiants and the fire back is itself heated, 70 thus adding to the heating efficiency of the stove.

The columnar radiants 2 are positioned over the holes or apertures 16 in the fuel plate with their lower ends resting between 75 the projections 17 and 18.

The fuel plate 6 has a nose piece 20 projecting from its forward edge approximately midway between its ends but at a lower level than the main portion of said plate, said 80 nose piece having a screw-threaded hole 21 to receive a screw 22 provided with a winged button 23. The screw 22 extends through a slot in a lug 24 which projects forwardly from the burner 14 and the winged button 85 23 of said screw bears against the lower side of the lug 24 to support the forward end of the burner.

The fuel plate 6, forwardly of the holes or apertures 16, is provided with a ridge 25 90 and the portion of the plate 6 which extends forwardly of said ridge is at a lower level than that portion of said plate which extends rearwardly of said ridge, as shown in Figs. 3 to 6, and the ends of such forwardly extending portion are provided with extensions having slots 5 extending longitudinally of such extensions. A pair of apertures or holes 26 are formed in one of said forwardly projecting portions, and the portion of the 100

plate 6 which surrounds each of said holes 26 is thickened as at 28 to afford greater strength at such parts.

The injector 27 has a pair of arms 29 which have screw threaded holes in their ends and the injector 27 is secured to the fuel plate 6 by screws passing through the holes 26, 26 in the fuel plate and engaging the screw threaded holes in said arms 29, 29.

10 The supporting structure is formed with a back wall and side walls, the side walls each having a forwardly directed extension 30, each such extension carrying at its end a screw threaded nut 31 or 15 hole whilst a lug projects rearwardly from approximately the center of the back 11. Said lug is provided with a screw threaded nut 32 or hole and ordinary screws 9 extend through the threaded openings in said lug 20 and in said arms 29 with their heads resting upon the floor, thus forming supports for the supporting structure. The screws may be adjusted to position the supporting structure correctly and, since there are only three 25 points of support, perfect flexibility is given to the supporting structure.

The back 11 of the structure also carries two uprights 33, 33 which are connected at their upper ends by a bar 34, and each of 30 said uprights is provided with a hole adjacent its upper end. The fire back 1 rests on the fuel plate behind the projections 18 and holes 19 and bears against the uprights 33, 33 and top bar 34 and is held in position by 35 bolts 35 which are passed through the holes in the upper ends of the uprights 33 and through the fire back 1.

The burner 14 is provided with a pair of rearwardly extending lugs 15, one adjacent 40 each end, and with a single lug 24 which projects forwardly intermediate its ends. The two lugs 15 are carried by the saddles 13 of the fuel plate and the slotted lug 24 is carried by the head 23 of the screw 22 45 since the lug 24 is slotted and, since the lugs 15 have a free movement in the saddles 13, the burner nozzles 36 can be correctly adjusted with regard to the openings 16 and columnar radiants 2 and will be 50 maintained at that position by the tightening of the screw 22; and since the burner is supported at three points perfect flexibility is given the burner under all conditions without affecting its position with 55 regard to the brilliants 2.

On the depressed forward portion of the fuel plate 6 is positioned a trivet 4 having a pair of screw rods 37, 37 on its under side. These rods 37 are provided with wing nuts 60 38, 38, the screws 37 extending through the slots 5 of the fuel plate, so that, after adjustment of the trivet 4 on the fuel plate, the wing nuts 38 will clamp the trivet 4 and fuel plate 6 together.

The forward edge of the trivet 4 is provided with a depending lip which engages a bar 7 and such bar 7 has a hole at each end, to receive bolts which extend through slots 40 formed in dogs 8 one of which stands at each forward corner of the stove. 70 By tightening wing nuts 39 on the bolts 40, the bar 7 and dogs 8 are secured together, so that after adjustment of the trivet 4 with the dogs 8 in position a tightening of the nuts 39 will fix the trivet in place. 75

As will be understood adjustment as to height of the stove is obtained by adjusting the screws 9 and adjustment as to depth is obtained by adjusting the screw rods 37 in the slots 5 of the fuel plate 6. 80

It will be understood that, although we describe and illustrate an inset gas stove the fuel plate and burner fittings are equally applicable to other types of gas stoves, and that in some types of stoves we may dispense with the slots 5 in the fuel plate and support the trivet 4, which may or may not have dogs, on the outside casing of the fire place or mantel. 85

What we do claim as our invention and 90 desire to secure by Letters Patent is:—

1. In a gas stove, a fuel plate having a row of apertures therethrough, and a hooked lug, a pair of saddle pieces depending from said plate, a supporting structure 95 for said fuel plate having a back wall with which said hooked lug engages and against which said saddle pieces bear, columnar radiants supported by said fuel plate above the apertures therein, a burner having nozzles 100 projecting through the apertures in the fuel plate, said burner having a pair of rearwardly extending projections resting in said saddle pieces and abutting said back wall, and adjustable means for suspending said burner from the fuel plate at a third point. 105

2. In a gas stove, a fuel plate having a row of apertures therethrough and a hooked lug on its rear edge, said plate further having a pair of saddle pieces depending therefrom in spaced relation, supporting means for the rear portion of said plate comprising a wall engaged by said hooked lug and resting against said saddle pieces, columnar radiants mounted on said fuel plate above said apertures, said plate having projections on its upper surface adjacent said apertures for properly positioning said radiants with respect to said apertures, a burner having nozzles extending into said apertures and a pair of rearwardly extending projections resting in said saddle pieces and abutting against said wall, said fuel plate also having a nose extending forwardly therefrom, said burner having a lug extending forwardly therefrom in alignment with said nose, hold fast means connecting said nose and said forwardly extending projection together, a 110 115 120 125

fire back supported by the fuel plate, said fuel plate having a second set of apertures therein between said radiants and said fire back, a trivet adjustably secured to the fuel plate and projecting over a portion thereof, and means for supporting the forward edge of said fuel plate.

In testimony whereof we have hereunto

set our hands in presence of two subscribing witnesses.

KENNETH AIRD.

SQUIRE ARCHIBALD DAVID WEBSTER.
